UNITED STATES PATENT OFFICE.

JOHN W. JACKSON, OF FALL RIVER, MASSACHUSETTS, ASSIGNOR TO AMERICAN MOISTENING COMPANY, OF BOSTON, MASSACHUSETTS, A CORPORATION OF MAINE.

LIQUID-SUPPLY SYSTEM.

Application filed August 7, 1923. Serial No. 656,240.

This invention relates to improvements in liquid supply systems. More particularly it has been developed for group control of centrifugal humidifiers, so as to render them 5 quickly responsive to stopping and starting impulses under local or remote control, manual or automatic.

In humidifiers of this type there is a constantly rotating electric motor and fan; and 10 there is a constantly rotating disk on the same shaft therewith, adapted to form and to throw a film of water centrifugally for its mechanical break-up into small particles by impact with atomizing blades. Each 15 unit has a well, which may be a simple piece of upright piping a few inches long, from which water is drawn to its rotating disk. The obvious means for stopping the humidifying action, as is desired intermittently, is 20 to close a valve in the supply pipe leading to the said well. The atomizing then stops when the water in the well has become exhausted. It is an object of the invention to provide other means, capable of controlling 25 all of a series of humidifiers simultaneously, so as to stop or to start them all by a single and possibly remote control device; to have this device such that it can be operated under automatic control; and to provide for practically instantaneous response to the stopping and starting impulses of the control 30 apparatus. These ends are attained by piping arrangements coordinated with the humidifiers and the water supply, by which 35 the force of gravity is employed for abstracting the water from all of the humidifier wells simultaneously, to a predetermined degree which is sufficient to stop their operation; and for restoring it when operation is 40 to be resumed. The principles and details of construction will appear in the description which follows. The apparatus of the 45 invention will naturally be designed in various ways depending upon the relative locations where the humidifying units are to be located. In ordinary cases these units will be all at a uniform level, or within a few inches of it, as, for example, in the various rooms of a building which are on the same 50 floor level, although in special cases single humidifiers may be considerably higher. However, there may be a great variety in such designs and it is to be understood that the particular system shown is only illustrative. It is intended that the patent shall 55

cover, by suitable expression in the appended claims, whatever features of patentable novelty exist in the invention disclosed, within the general scope of the above stated objects, it being understood that the type of construction of humidifier, and the broad idea of feeding the same with a single line of piping did not originate with me.

In the accompanying drawings,

Figure 1 is an elevation showing an installation of a humidifying system embodying my invention;

Figure 2 is an elevation of a part of the same on a larger scale, showing details of the water control; and

Figure 3 is a medial vertical section through a two-way valve which may be used in the water control, showing water passages.

Referring to the drawings, the several 75 humidifying units illustrated are of the centrifugal type, in which water is drawn from a well 12 to a rotor disk 14 (Fig. 2) which films and throws it against a multiplicity of fixed blades (not shown), thus atomizing it 80 to fine fog-like particles suitable for absorption in and distribution about the room by a blast of air provided by a fan within the casing 15 (Fig. 1). In the particular style 85 illustrated the fan, rotor and water pump 18 are all assembled on the vertical shaft 16 of an electric motor 17; but the invention is applicable to other arrangements, as for example where the shaft is horizontal and it 90 may also be applied to certain other types of humidifiers. Whenever it is desired to stop the humidifying during regular service it is usually desired to continue the running 95 of the fan, for circulation of air. Hence the obvious method of turning off the electric current is not available. In the system 100 illustrated, water is maintained at constant level in the several humidifying units, when they are operating as humidifiers, by supplying their several wells from an open tank 105 22 having a ball-float valve which controls the tank supply 24, so as to keep the water in the tank at a predetermined level L—L corresponding approximately to that at 110 which the water is to stand in each individual well. Each distributing pipe 20, which is the trunk supply pipe for a series of humidifiers, runs at a lower level, preferably fairly close to the bottom of the humidifiers; but it could be set much lower, as, for ex-

ample, under the floor, with vertical risers to the humidifiers and to the supply tank. The flow of water to any humidifier may be cut off by simply closing a long handled 5 valve 26 in its branch connection from the distributing line; but if this is done the water already in the well will continue to be atomized and discharged into the air until exhausted. This will ordinarily take several 10 minutes, and during that time the humidity added to the air may be more than is wanted; and may even cause serious trouble.

The present invention while not displacing 15 such means for discontinuing the supply of water, seeks to provide other means for stopping the humidifying, and for doing so practically instantaneously. This is done by abstracting the water from the pump. It 20 is a further feature to remove the water without loss of any appreciable quantity thereof; and to replace it for quick starting at will. To these ends there is provided in the trunk supply pipe, at any convenient 25 point, a two-way valve 28 having one passage leading through the valve, from tank to trunk line and thus to humidifiers while the second way is closed; and having its second passage connecting the trunk line with a 30 drain, while the supply to the trunk line from the tank is closed. By this means the water can be drained out of the wells 12, resulting, if the drain led downward from the valve, in emptying the trunk line pipe 35 and wells. It is a further feature to introduce an upward loop 30 to provide a limited drain 32. The height of this loop is such as to determine a level $l-l$ of water, herein called the stand-by level, below which water 40 will remain in the trunk line pipe and the drainage from the wells is stopped just below the reach of their several pumps.

When the humidifiers are to be operated 45 the two-way valve 28 is set so that there is a passage through it from the tank to the several wells; and the connection through the loop 30 to the limited drain 32 is closed. When it is desired to stop the humidifier discharge of water, the two-way valve is 50 shifted, either manually or by automatic apparatus 34; which may be of any well known or suitable type ordinarily controlled by a humidistat (not shown) and operating by compressed air or by electricity. The type 55 illustrated is assumed to be controlled by flow of compressed air through pipe 33 from the humidistat to a diaphragm motor 34 whose plunger is connected by a bell crank lever 36 to the stem of the two-way valve 28. The 60 shifting of the valve shuts off the flow from the tank (see Figure 3) and throws the portion of the trunk line 20 which is on the humidifier side of valve 28 open to the vertical limb of the loop 30 leading to the drain. 65 Discharge flow immediately begins and the

water in the wells instantly falls from the level $L-L$ to the level $l-l$. The amount of water flow involved in this is very small if the wells are mere vertical pipes an inch or so in diameter, as they preferably 70 are. Flow then ceases. Siphon action may be prevented by a vent to atmosphere from the top of the loop, as by pipe 30a. The trunk line pipe 20 remains filled and water remains standing in the lower parts of wells, 75 preferably at the maximum height at which it can stand with security that it will not be picked up by the continuously rotating pump.

The time for escape of water is thus reduced to a minimum, since the amount discharged is so small, causing stoppage of the humidifying action almost simultaneously with the shifting of the two-way valve. Upon this valve being oppositely shifted, so as to 80 connect the tank to the trunk line, the water in the wells need only rise from the low or stand-by level $l-l$ to that $L-L$ of the water in the tank, in order for the pump to begin taking it to the rotor. This rise takes place 85 very quickly under gravity pressure of the higher water level in the tank; and the atomizing at once follows. As a result the time required to change the water level in the wells is practically negligible. And 90 since the operation of all the humidifiers is affected simultaneously, uniform distribution of moisture throughout the room is controlled readily, with rapid response of the apparatus to changed conditions whenever 95 detected by the automatic apparatus, or whenever the control is operated by hand, without disturbing the air circulation, and with a minimum wastage of water.

Although illustrated as it may be applied 100 with a piping system and a series of humidifying units, the broader aspects of the invention are not limited to that; for it can be used with a single unit, suitable arrangements being made, as on the principles above 105 explained, to raise or lower the level at which well water stands, to and from predetermined elevations. In this connection it will be understood that the well drainage which is provided is not necessarily arranged to 110 take the water out of the system; but that it is sufficient if the level of supply water is so readjusted that it stands below the reach of the water lifting device of the humidifier; and any device that will bring that about 115 may serve.

Moreover the term "well" is to be taken in a broad sense as indicating any local receptacle or source from which the water or other liquid is lifted or otherwise flows, 120 upward or downward, to the apparatus. In the case of the centrifugal humidifiers described it is most convenient to have this below the rotor, but the use of the term "well" does not signify that it is necessarily 125

so located. Nor is the invention limited to use with centrifugal humidifiers, nor indeed, to the particular liquid, water, with which humidifiers are ordinarily operated; but the 5 water is typical of any liquid with which the humidifier may be operated, and the references to humidifiers are to be taken as standing for any apparatus in which the liquid is wanted intermittently, rather than 10 as restrictive, unless a contrary meaning appears necessary.

I claim as my invention:

1. A liquid supply system for apparatus, comprising, in combination, a constant-level 15 reservoir, remote from the apparatus; a local supply well at the apparatus, connected with the reservoir and adapted to hold liquid from the reservoir at the reservoir level; a limited drain for the well and its said connection, positioned and connected to drain the well, the limit being at a stand-by level; and inter-connected valve means controlling both the supply from reservoir and the said drain, adapted for simultaneous shut-off of 25 the reservoir supply and opening of said drain.

2. A liquid supply system for apparatus, comprising, in combination, a reservoir relatively remote therefrom, in which liquid is 30 maintained at a constant supply level; a local well, for the immediate supply of the apparatus, adapted to hold liquid at the level of said constant supply, and connected with the reservoir; a standby drain for said 35 well, arranged at a level which is close below the said supply level, which drain is adapted, when open, to drain the liquid in said well down to said standby level; and interconnected valves operating simultaneously and oppositely, the one closing when the other opens, controlling respectively the 40 said connection from reservoir and the said drain.

3. The combination, in a system comprising a well and means for lifting liquid therefrom, of a system of piping for supplying said well maintained full of said liquid; a device for changing the level at which liquid is maintained in the well, between an 45 elevation at which it is within reach of said lifting means and an elevation at which it is not within reach thereof, comprising a non-siphonic drain at a level close below the lowest level at which the liquid is within 50 reach of said lifting means; and means to open and close the drain.

4. In a supply system for apparatus requiring liquid intermittently, the construction of a local well arranged for flow of the 55 liquid thence to the apparatus, with means for maintaining a remote liquid supply at a predetermined level; a pipe thence to the well, whereby the liquid may be fed thereto

by gravity, to the same level in the well; a drain for said well, normally closed, comprising a loop rising from said pipe and descending to a discharge, with the crest of the loop vented to air and arranged at a level too low for said flow from well to apparatus to occur; and means for closing said pipe and opening said drain, whereby the well liquid falls to said crest level.

5. A humidifying system comprising in combination a humidifier having means for lifting water to be atomized; supply means 75 for normally maintaining the water at the humidifier at a predetermined level within reach of the lifting means; and control means for simultaneously cutting off the supply and withdrawing water at the humidifier, to bring the water at the humidifier to a second predetermined level which is below the effective reach of the lifting means thereby stopping atomization.

6. In a system comprising a well and means for flow of liquid therefrom to be atomized, the combination of apparatus for maintaining a liquid supply at a predetermined level; a pipe thence to the well, whereby liquid may be fed thereto by 85 gravity, to the same level therein; a non-siphonic drain from said pipe, normally closed; there being in said drain a loop rising from the pipe to a certain level whereby the liquid is maintained in said well at a 90 level below the possibility of said flow when the drain is open.

7. A liquid supply system for a plurality of humidifiers each having a local well for the liquid and means to lift the liquid therefrom to be atomized, comprising in combination a reservoir relatively remote therefrom in which liquid is maintained at a constant level, a pipe thence to said local wells for maintaining liquid therein at said level, and means associated with said pipe whereby the supply from said reservoir is cut off and the liquid in each said local well simultaneously withdrawn through the pipe, below said 100 level, to stop the atomization.

8. A liquid supply system for apparatus, comprising, in combination, a constant-level reservoir; a supply well at the apparatus, connected with the reservoir and adapted to hold liquid therefrom at the reservoir-level 115 for operation of the apparatus; a limited drain for the well and its connection, the limit being at a stand-by level close below the limit where said apparatus becomes inoperative for lack of supply; and interconnected valve means controlling simultaneously the supply from reservoir and the said drain from well.

Signed at Boston, Massachusetts, this twenty-fifth day of April, 1923.

JOHN W. JACKSON.
